UNITED STATES PATENT OFFICE

2,545,949

DESK ELEVATOR

Martin Fox, Chicago, Ill., assignor to
The Seng Company

Application July 11, 1945, Serial No. 604,428

4 Claims. (Cl. 45—139)

1
This invention relates to an improved adjusting device utilizing a pair of opposed wedge members, and more particularly to a device for adjustably supporting heavy objects, such as desks, office machines, and the like.

The primary object of the invention is to provide an adjustable support which is easily installed and may be adjusted at various heights without impairing the strength and rigidity of the support, or detracting from the appearance of the equipment.

A further object of the invention is to provide an adjustable "island type" support for a desk, which will not come apart when the desk is lifted and has ample strength to withstand lateral or end thrusts which may occur through moving the desk from the floor.

The invention is illustrated in a preferred embodiment in the accompanying drawings, in which—

Figure 1 is a perspective view of an office desk equipped with a pair of adjustable island supports; Fig. 2, a perspective view of one of the island supports in retracted position; Fig. 3, a view similar to Fig. 2 in extended position; Fig. 4, a vertical sectional view of the supports in collapsed position; Fig. 5, a similar longitudinal sectional view with the top-block partially extended; Fig. 6, a vertical sectional view, taken as indicated at line 6—6 of Fig. 2; Fig. 7, a vertical sectional view, taken as indicated at line 7—7 of Fig. 2; and Fig. 8, a vertical sectional view, taken as indicated at line 8—8 of Fig. 2.

In the embodiment illustrated, a base-block 9, preferably made of wood, is provided at its top end portion with oppositely inclined faces 10, which are flanked by shoulders 11 which form a guide for movable wedge members 12. The base-block may be provided with the usual antifriction domes 13, and preferably the structure is surrounded by an ornamental sheet metal skirt 14 which is secured to the base-block by screws 15. A stop 16 may be secured to one end of the block 9 by a screw 17 to limit the outward travel of one of the wedge members 12.

A top-block 18 is superposed on the base-block 9 and has in its lower face inclined faces 19, which cooperate with the inclined faces 10 in the base member to form opposed wedge-shaped openings for the wedge blocks 12. The inclined faces 19 are flanked by shoulder portions 20 which form upper lateral guides for the wedge members.

In order to keep the base-block and top-block

in proper registration at all times, the base-block is provided with a pair of leader pins 21, which extend upwardly into registering apertures 22 in the top-block. In order to yieldingly urge the assembly together at all times, a pair of registering holes 23 are drilled through the base-block and top-block, and a pair of tension springs 24 are inserted therein. Cross pins 25 hold the upper ends of the springs and after the top-block has been attached to the structure it is to carry, such as a desk 26, the base-block is slipped into position and the lower ends of the springs are drawn out by means of a hooked tool and fastened over bottom cross pins 27.

A shaft 29 is provided at one end with a left hand screw thread 30 and passes through and makes threaded engagement with one of the wedge blocks 12. The other end of the shaft 20 has a right hand screw thread 31 which passes through and makes screw threaded engagement with the opposed wedge member 12. Preferably, one end of the shaft is provided with a slot 32, to receive a screw driver, and the metal skirt 25 14 is apertured, as indicated at 33, to permit insertion of a screw driver or key, not shown. The shaft is also provided near its central portion with a grooved pulley 34, and the blocks have cutout portions 35, to accommodate it. A leader pin 36 extends from the top-block 18 through the pulley into a registering opening 37 and prevents axial movement of the shaft 29.

After the islands have been installed on the desk, or the device which is to be supported, it is merely necessary to use a screw driver to raise the desk to a desired level or to raise one island with respect to the other. It will be noted that the wedge members are widely separated, so that a firm support is provided at widely spaced points, which eliminates teetering. The leader pins take up any lateral or longitudinal thrust between the base-block and top-block, and the springs prevent the parts from becoming disassembled accidentally.

The foregoing detailed description is given for clearness of understanding only, and no unnecessary limitations should be understood therefrom, for some modifications will be obvious to those skilled in the art.

50 I claim:

1. A vertically adjustable island support for a desk comprising: a long, low base-block; a top-block superposed on said base-block and adapted to be secured to the bottom of a desk; guide means for maintaining said blocks in regis-

tion; and means cooperating with the base-block and top-block for controlling their spaced relationship; resilient means for holding the assembly together when it is moved about as a unit; and a protective metal skirt surrounding the base-block and top-block and secured to the base-block.

2. An elevator device for the purpose set forth, comprising: a long, low base block provided in its upper face at its end portions with short, spaced, inwardly and upwardly inclined faces; a long, low top-block provided in its lower face at its end portions with short, spaced, inwardly and downwardly inclined faces adapted to cooperate with the inclined faces of said base block and form opposed wedge-shaped openings; a rotatable shaft between said blocks provided with right and left screw threads; a pair of wedge members in the opposed wedge-shaped openings and threaded to said shaft; guide means disposed between said wedge members for maintaining the top-block and the base-block in registered superposed position; and a pair of springs tensioned on the top block and the base block between the wedge members to yieldingly resist separation of the blocks, said springs comprising the sole means preventing separation of the blocks when the device is lifted by gripping the top block.

3. A device as specified in claim 2 wherein registering apertures extend continuously

through the base block and the top block, and the springs are secured to pins extending into said apertures.

4. A vertically adjustable island support for a desk comprising: a pair of long, low registering separable wooden blocks in superposed relation, one of said blocks being provided near its ends with short inclined portions so as to provide opposed wedge-shaped openings between said blocks; a pair of metal wedge members in said openings; a shaft between said blocks making a right hand screw threaded connection with one of said members and a left hand screw threaded connection with the other member; leader pins extending between said blocks to maintain registration; and springs providing the sole means for holding the assembly together when it is lifted by gripping the top block.

MARTIN FOX.
